UNITED STATES PATENT OFFICE.

HIRAM R. MALLINSON, OF NEW YORK, N. Y.

DESIGN FOR A TEXTILE FABRIC.

48,120.

Specification for Design.

Patented Nov. 9, 1915.

Application filed June 12, 1915. Serial No. 33,804. Term of patent 3½ years.

To all whom it may concern:

Be it known that I, HIRAM R. MALLINSON, a citizen of the United States, residing at New York city, in the county of New York and State of New York, have invented a new, original, and ornamental Design for a Textile Fabric, of which the following is a specification, reference being had to the accompanying drawing, forming part thereof.

The single figure of the drawing is a plan view of a portion of a textile fabric illustrating my new design.

I claim:

The ornamental design for a textile fabric as shown.

HIRAM R. MALLINSON.
